Specification for Design.

Patented Sept. 18, 1917.

Application filed July 18, 1917. Serial No. 181,419. Term of patent 7 years.

To all whom it may concern:

Be it known that I, NATHAN DREYFUS, a citizen of the United States, residing in the borough of Manhattan, city, county, and State of New York, have invented a new and original ornamental Design for Clocks, of which the following is a specification, reference being had to the accompanying drawings, forming part thereof.

Figure 1 is a front elevation showing the characteristic features of my design for clocks; and

Fig. 2 is a side elevation.

I claim:

The ornamental design for a clock, as shown.

NATHAN DREYFUS.
